UNITED STATES PATENT OFFICE.

WILLIAM D. MACQUESTEN, OF NEW YORK, N. Y., ASSIGNOR TO CHARLES L. EDGAR, TRUSTEE, OF BOSTON, MASSACHUSETTS.

TENSION-BRACKET FOR TROLLEY-WIRES.

SPECIFICATION forming part of Letters Patent No. 429,816, dated June 3, 1890.

Application filed October 9, 1889. Serial No. 326,415. (No model.)

To all whom it may concern:

Be it known that I, WILLIAM D. MACQUESTEN, of New York city, county of New York, State of New York, have invented an Improvement 5 in Pull-Off Brackets, of which the following description, in connection with the accompanying drawings, is a specification, like letters on the drawings representing like parts.

10 This invention relates to electric railways, and has for its object to provide a pull-off bracket of novel construction, as will be described, especially adapted to be employed on curved portions of the road, whereby the 15 trolley-wire may be made to more clearly assume the arc of a circle.

In accordance with my invention my improved pull-off bracket consists, preferably, 20 of a shoe to support the wire, a rod secured to said shoe and provided at one end with a covering of insulating material, and a swivel fitted over the insulated end of the said rod and adapted to turn thereon, the said swivel being adapted to be connected by a rod or wire 25 to a fixed structure located at the side of the road.

My invention in a pull-off bracket therefore consists, essentially, in the combination, 30 with a support for the trolley-wire, of a rod connected to the said support and provided with a cap of insulating material, and a swivel fitted upon said cap and adapted to be connected to a post or upright, substantially as will be described.

35 Figure 1 represents a sufficient portion of a trolley-wire, a post or upright, and a pull-off bracket connected to the trolley-wire and to the post or upright to enable my invention to be understood; Fig. 2, a top view, partially 40 in section on an enlarged scale, of the pull-off bracket and a portion of the trolley-wire; and Fig. 3, a modification to be referred to.

My improved pull-off bracket consists, preferably, of a metallic shoe *a*, provided with an 45 upturned flange on its under side to form a groove, into which the trolley-wire *a'* is laid, substantially as shown and described in another application, Serial No. 317,558, filed by me July 15, 1889. The shoe *a* is provided 50 with a rod or arm *a'*, having at its end a cap or covering *a'*, of insulating material, prefer-

ably molded or otherwise fixed upon a threaded shell or sleeve *a'*, adapted to be secured upon the threaded end of the rod *a*. The insulating-cap *a'* is preferably enlarged 55 at its rear end, and has fitted upon it a swivel *b*, which is preferably connected by a rod *b'* with the threaded end of a swivel *b*, connected, as shown, by a rod *b* to a cap *b'* on an upright or post *b*, which in practice is usually 60 located at the side of the road, the rod *b* being shown as threaded at its end and extended through a threaded eye of a lug or ear *b* on the cap *b'*, and secured thereto by a nut *b*. The shoe *a* is made of considerable length to 65 afford a substantially long bearing for the trolley-wire *a'*, so that when the pull-off bracket is tightened up, as by revolving the swivel *b* on the rod *b'*, the trolley-wire will be made to more nearly assume the arc of a circle, it 70 being rigidly held in place and prevented from swaying, so that the trolley-wheel carried by the car will be maintained in electrical contact with the trolley-wire as the car travels around the curve.

75 Instead of making the cap as a shell *a'*, provided with the covering *a'* of insulating material, the said cap may be made entirely of insulating material, as shown in Fig. 3.

Referring to Figs. 2 and 3, it will be noticed 80 that the cap is provided with inclined sides, as 2, to fit the inclined opening through the end of the swivel *b*, through which it is extended, and as a result of this construction it will be seen that when the pull-off bracket 85 is placed under tension, as by turning the swivel *b*, the insulating material is compressed—that is, it is subjected to compression rather than to tension—and the said insulation is thereby enabled to stand a long time 90 without being replaced.

I prefer to employ the shoe *a* and also the rod *b'* and swivel *b*, connected to the post *a*; but I do not desire to limit myself to the exact construction shown, as other well-known 95 forms of support may be used instead of the shoe *a*, and the swivel *b* may be connected by a wire to the cap *b'*.

I claim—

1. In a pull-off bracket, the combination, 100 with a support for the trolley-wire, of a rod connected to the said support and provided

with a cap of insulating material, and a swivel fitted upon said cap and adapted to be connected to a post or upright, substantially as described.

5 2. In a pull-off bracket, the combination, with a support for the trolley-wire, of a rod connected to the said support and provided with a cap of insulating material having inclined sides, and a swivel having an inclined
10 opening through which the cap is extended,

said swivel being adapted to be connected to the post or upright, substantially as described.

In testimony whereof I have signed my name to this specification in the presence of two subscribing witnesses.

WILLIAM D. MACQUESTEN.
